PURIFICATION OF HYDROCARBONS

William Roberts Wood, Louisville, Ky., assignor
to The Girdler Corporation, Louisville, Ky., a
corporation of Delaware

Application June 10, 1938, Serial No. 212,929

3 Claims. (Cl. 196—32)

This invention relates to the treatment of hydrocarbon compounds in liquid state for the removal of sulfur compounds therefrom.

The sulfur impurities commonly found in hydrocarbons particularly those obtained from petroleum oils, may include hydrogen sulfide which may be that derived from the original petroleum oil or as a result of certain reactions employed in the refining processes, and particularly in the cracking process. Hydrogen sulfide is of a strongly acidic nature and may be removed from such hydrocarbon liquids by reacting it with an agent of an alkaline nature. However, the reaction between a strongly acidic material such as hydrogen sulfide, and a strongly alkaline inorganic material such as caustic soda or the like, results in a relatively stable by-product from which the hydrogen sulfide cannot be readily removed in gaseous form to regenerate the alkaline reagent.

Other sulfur compounds commonly found in such hydrocarbon liquids are mercaptans, which are of a weak acidic character and form readily decomposable compounds with alkaline treating agents. The by-product resulting from the reaction of the mercaptans and the alkaline treating agent may be readily decomposed to liberate the mercaptans in gaseous form and regenerate the alkaline treating agent by the action of heat in a reactivator.

It frequently happens that the liquid hydrocarbons requiring treatment may contain both hydrogen sulfide and mercaptans. If such hydrocarbons be treated with a strongly alkaline inorganic reagent, the portion of the latter which has reacted with the hydrogen sulfide cannot be readily regenerated for reuse. If a weak alkaline agent be employed which will react with the hydrogen sulfide to form a readily decomposable by-product, it will not necessarily react with all of the weakly acidic mercaptans. Thus, if a strong inorganic alkali be employed no cyclic system can be employed, since large quantities of sodium sulfide, which cannot be regenerated are formed when soda is used as the alkaline material, and if a weakly alkaline agent be employed there is no assurance of complete removal of the mercaptans.

It has been proposed in the Bottoms Reissue Patent 18,958, to use alkaline amines for removing sulfur compounds from gaseous mixtures, and in a cyclic system, and this has proved very efficient and satisfactory in commercial practice, but due to the special problems involved in the treatment of liquid hydrocarbons it has not

been thought practicable to employ such alkaline amines in the treatment of liquid hydrocarbons.

Although alkaline amines of the concentration recommended in the Bottoms reissue patent, namely about 50%, are not practical for removing sulfur compounds from liquid hydrocarbons, it has now been discovered that hydrogen sulfide may be effectively and satisfactorily removed by the use of an alkaline amine of comparatively low concentration, and circulated in a cyclic system with regeneration and liberation of the sulfur compound.

It has been further discovered that where the liquid hydrocarbon contains both hydrogen sulfide and mercaptans, the hydrogen sulfide may be first removed by an alkaline amine flowing in a cyclic system with regeneration, and that thereafter the mercaptans may be removed by a stronger alkaline reagent, which due to the weak acidic character of the mercaptans, may be readily regenerated so that the alkaline reagent may here also flow in a cyclic system with regeneration.

By using two separate closed treating cycles employing basic agents and operating in succession on the liquid hydrocarbon these sulfur compounds may be removed without the development of stable by-products, and with regeneration of the basic agents in both cycles. The strongly acidic sulfur compound is removed by the solution of a weakly alkaline compound, and the weakly acidic sulfur compound is removed by a solution of a strongly alkaline compound.

It has been further discovered that by the use of dilute solutions containing less than 30% of the amine base, and preferably in the form of monoethanolamine, the amine solution saturated with hydrogen sulfide will have a lower viscosity than the fresh solution, and a ready separation of the saturated solution from the liquid hydrocarbon can be effected. Furthermore, the solution containing hydrogen sulfide has a higher specific gravity than the fresh solution and the liquid therefore becomes proportionately heavier than the liquid hydrocarbon which also assists in the separation. Furthermore, the solution saturated with hydrogen sulfide has a greater surface tension than the fresh solution and therefore less tendency to emulsify. Heretofore danger of emulsification of organic alkaline materials with the liquid hydrocarbons has been considered an obstacle to the use of such materials. Thus, the results obtained by the use of amine solutions of com-

paratively low concentration are contrary to prior teachings to the effect that the efficient operation required relatively concentrated solutions of about 50% or more of the amine.

- 5 The present process may be carried out in various types of apparatus. In the accompanying drawing there is shown somewhat diagrammatically a type of apparatus which may be employed. The liquid hydrocarbon, for instance a prime cut 10 naphtha or a virgin naphtha, may be delivered through a pipe 10 into a mixing chamber 11 in which it is thoroughly mixed with an amine solution which is immiscible therewith, and delivered through the pipe 12. The two liquids may flow 15 in the same direction and intermixing may be effected in any suitable manner, as for instance by baffles or by mechanical agitation, or by means effecting repeated changes in the direction of flow through the mixer. The amine will react 20 with the hydrogen sulfide and the mixture of liquid hydrocarbon and amine saturated with hydrogen sulfide may pass out through the pipe 13 to any suitable form of separator 14. The separation may be effected by the difference in 25 specific gravities of the two liquids, and by a mere settling process, or the separator may be in the form of a centrifuge or any other type of apparatus utilizing difference in specific gravity for effecting separation. The lighter liquid hydrocarbon free of hydrogen sulfide may be drawn off from the top of the separator through the pipe 15, and into the second stage of the process in the event that it contains mercaptans, but if it is 30 free of mercaptans the liquid hydrocarbon free of hydrogen sulfide may be delivered from the pipe 15 through the pipe 16 to any desired point of disposal.

The solution of the relatively weak amine saturated with hydrogen sulfide may be returned from 40 the separator 14 through a pipe 17 into a reactivator 18 where the liquid is heated or subjected to sub-atmospheric pressure, to remove the hydrogen sulfide in gaseous form through the vent 19. The reactivator may be of the type shown 45 in the Bottoms patent above referred to. The reactivated and purified amine solution may be delivered through a pipe 20 by means of a pump 21 and back through the pipe 12 entering the mixing chamber 11, and this pipe 12 may include 50 a cooler 12' for removing the heat imparted to the liquid by the heating coil 18' in the reactivator 18.

It is unnecessary to employ any flash drums or the like for preventing the liquid hydrocarbon 55 from entering the reactivator 18, since it is not necessary to conduct the process at elevated temperatures or pressures, and no loss of the amine results from vaporization in the reactivator 18 or the separator 14. Thus a very economical process results.

Assuming that the liquid hydrocarbon to be treated contains both hydrogen sulfide and mercaptans, the liquid hydrocarbon may be treated as above described by the amine solution which 60 will remove the highly acidic hydrogen sulfide without removing appreciable quantities of the weakly acidic mercaptans, most of which will remain in the liquid hydrocarbon passing through the outlet pipe 15.

The liquid hydrocarbon may then be delivered 70 to the second phase of the process which may be carried out by apparatus very similar to that employed in the first phase. The liquid hydrocarbon free of hydrogen sulfide, and containing the mercaptans, will flow through the pipe 30 to

a mixing chamber 31 where it is mixed with a solution of any strongly alkaline inorganic material entering through the pipe 32. The strongly alkaline material may be a 15% solution of caustic soda, which is immiscible therewith and which 5 will react with the mercaptans, and the mixture of the alkaline solution saturated with mercaptans and the liquid hydrocarbon may be delivered through a pipe 33 to a separator 34. The two liquids will separate by gravity in the separator 10 34, or may be separated mechanically by a centrifuge, and the purified liquid hydrocarbon will be delivered through the pipe 35. The alkaline solution saturated with the mercaptans may be drawn off through the pipe 37 and delivered to 15 a reactivator 38 heated by a coil 38'. The mercaptans will be volatilized and delivered in gaseous form through the vent 39, and the reactivated alkaline solution returned through the pipe 40 and pump 41 to the pipe 32 which may contain 20 a cooler 32'.

By means of the present process liquid hydrocarbons may be treated without requiring a prior gasification stage, and the purification may be carried out at low temperature and at a low cost. 25 It is not necessary to employ high treating temperatures, which is frequently found necessary in the treating of gaseous hydrocarbons where there is present the danger of condensation.

The process is very economical, due to the fact 30 that little, if any, of the amines or alkaline solutions are lost, and there is no appreciable amount of hydrocarbon lost in the solution going to the reactivator. This is due in large measure to the use of a relatively low concentration of amine 35 instead of the higher concentration heretofore disclosed for the treatment of mixed gases.

Reference has been made to monoethanolamine as the preferred weakly alkaline material. The term "amine" as used in this case is intended to 40 include any of the other amines or analogous organic bases defined in the Bottoms patent above referred to as an amine selected from the group consisting of aliphatic and cycloparaffin amines, and which is free from carboxyl or carbonyl 45 groups, and which has a boiling point not substantially below 100° C. Any of these may be employed within the scope of the present invention. The amine employed is preferably an aliphatic amine, and preferably one including a 50 hydroxyl group, such amines being known as alkyl amines.

In the specific example given there is reference to the use of naphtha, but any other appropriate type of liquid hydrocarbon which has a distinctly 55 different specific gravity from the alkaline solution may be employed, such for instance, as kerosene, gasoline, or the like. Furthermore, the invention may be employed in the treatment of hydrocarbons in liquid state under pressure conditions sufficient to maintain normally gaseous hydrocarbons in liquid condition during the purification of the same. As will be apparent, other forms and arrangements of apparatus may be 60 made for carrying out the invention without departing from the scope of the same.

Having thus described my invention, what I claim as new and desire to secure by Letters Patent is:

1. The process of removing sulfur compounds 70 from liquid hydrocarbons and separately recovering weakly acidic sulfur compounds and strongly acidic sulfur compounds in gaseous form, which includes first mixing the hydrocarbon in a liquid state with a solution containing not more than 75

30% alkylol amine and insufficiently basic to react in a substantial measure with mercaptans and other weakly acidic sulfur compounds in said hydrocarbon, but sufficiently basic to react with hydrogen sulfide and other strongly acidic sulfur compounds therein, separating said hydrocarbon and said solution, thereafter mixing said hydrocarbon in a liquid state with a solution of an alkali sufficiently basic to react in substantial measure with mercaptans and other weakly acidic sulfur compounds in said hydrocarbon, separating said hydrocarbon and said second mentioned solution, and separately heating said solutions to liberate therefrom the strongly acidic sulfur compounds and the weakly acidic sulfur compounds in gaseous form and regenerate the solutions.

2. The process of removing sulfur compounds from a hydrocarbon in a liquid state, which includes maintaining a cyclic flow of a solution containing not over 30% of an alkylol amine through a contact chamber, a separator and a heated regenerator, maintaining a separate cyclic flow of a solution of a strong alkali through a contact chamber, a separator and a heated regenerator, and circulating a hydrocarbon in liquid state through said contact chamber and separator

of the first cycle, and then through the contact chamber and separator of the second cycle, to separate the strongly acidic sulfur compounds from the hydrocarbon in the first cycle and weakly acidic sulfur compounds from the hydrocarbon in the second cycle and to deliver the strongly acidic sulfur compounds and the weakly acidic sulfur compounds in gaseous form and separately from said heated regenerators.

3. The process of purifying hydrocarbons in a liquid state and recovering hydrogen sulfide and mercaptans separately in gaseous form, which includes passing the liquid hydrocarbon in contact with a solution of an alkylol amine of a concentration not over 30%, to thereby remove from the liquid hydrocarbon the hydrogen sulfide present, separating the liquid hydrocarbon from the solution, mixing the liquid hydrocarbon with a solution of a strong alkali to thereby remove the mercaptans, separating the hydrocarbon from said last mentioned solution, and separately heating said solutions to separate therefrom the hydrogen sulfide and the mercaptans in gaseous form and regenerate said solutions.

WILLIAM ROBERTS WOOD.
